US0D1072174S

(12) **United States Design Patent** (10) **Patent No.:** **US D1,072,174 S**
Workman et al. (45) **Date of Patent:** **** Apr. 22, 2025**

(54) **WATER FILTER**

(71) Applicant: **Haier US Appliance Solutions, Inc.**,
Wilmington, DE (US)

(72) Inventors: **Joshua K. Workman**, Louisville, KY
(US); **Keith A. Snyder**, Newburgh, IN
(US)

(73) Assignee: **Haier US Appliance Solutions, Inc.**,
Wilmington, DE (US)

(**) Term: **15 Years**

(21) Appl. No.: **29/872,737**

(22) Filed: **Mar. 17, 2023**

(51) LOC (15) Cl. **23-01**

(52) U.S. Cl.

USPC **D23/209**

(57) **CLAIM**

The ornamental design for a water filter, as shown and described.

DESCRIPTION

FIG. 1 is a front elevation view of the water filter. The rear elevation view, which is not shown, is the same as the front elevation view.

FIG. 2 is a left side elevation view of the water filter. The right side elevation view, which is not shown, is the same as the left side elevation view.

FIG. 3 is a top plan view of the water filter.

FIG. 4 is a bottom plan view of the water filter.

FIG. 5 is a top perspective view of the water filter.

FIG. 6 is a bottom perspective view of the water filter; and,

FIG. 7 is another perspective view of the water filter. The broken lines in FIGS. 1-7 show unclaimed subject matter only and form no part of the claimed design.

1 Claim, 7 Drawing Sheets
